CLAIM

The ornamental design for a life saving flotation device, as shown and described.

DESCRIPTION

FIG. 1 is a front elevation view of a life saving flotation device showing my new design;

FIG. 2 is a rear elevation view thereof;

FIG. 3 is a right elevation view thereof;

FIG. 4 is a top plan view thereof;

FIG. 5 is a bottom plan view thereof; and,

FIG. 6 is an isometric view thereof showing the two bottom straps in an alternate position.
